PACKAGE LINER

Charles G. Wood, Adrian, Mich., assignor to Simplex Paper Corporation, Adrian, Mich., a corporation of Michigan

Application December 16, 1933, Serial No. 702,681

4 Claims. (Cl. 217—3)

This invention which relates generally to package liners is adapted specially for use in the packing of fruits vegetables, and the like, in baskets or hampers. A disclosure of certain features of my invention is contained in my application filed March 16, 1932, Serial No. 599,189.

The liner which is made of a suitable paper, such as chip-board, is of elongated form bent around to present its two ends in meeting relation. The present invention is concerned particularly with a connection between the meeting ends of the liner. According to the present improvements, I provide for a slip connection between the liner ends made from interfitting tongues and slots, this connection being rendered permanent, if desired. No parts other than elements integral with the liner are required for this purpose, although I prefer to use a sticker to join the locking tongues together. The operation of connecting the liner ends may be performed expeditiously and simply without any mechanical aid whatsoever.

A suggestive embodiment of my invention is set forth in the accompanying drawing wherein—

Figure 1 shows in perspective the present liner having its two ends connected by tongues which are joined by a sticker;

Fig. 2 is an enlarged vertical section through the connected ends of the liner taken on line 2—2 of Fig. 1;

Fig. 3 is a view in elevation of the two ends, slightly separated;

Fig. 4 is a detail in section taken on line 4 of Fig. 1; and

Fig. 5 is a view in perspective of the liner applied within a bushel basket for protecting a column of fruits, vegetables, or the like from contact with the basket walls.

A liner L of conventional form is illustrated in the drawing. As shown, it is of elongated form with its opposite ends brought together for connection. For convenience in packing and shipping, the liner is creased or folded at diametrically opposite points 10 so that it may lie flat. In order to conform to a container whose walls are tapered, for example, a bushel basket B, the opposite longer edges of the liner are of arcuate shape whereby the resulting liner will acquire the form of a truncated cone.

In the construction shown, one liner end a is provided with opposed tongues t extending toward each other and meeting centrally of the opposite edges of the liner. The tongues are defined by a single slit s extending transversely

slightly from the liner end, a cut c extending inwardly from the liner end to the slit to separate the two tongues. By this construction I provide opposed tongues disposed transversely of the liner at one end, formed by slits extending through the center region part way toward the opposite edges.

Each opposite liner end b is equipped with a pair of openings o in the form of closed slots elongated in the direction of the liner length, and disposed about opposite the tongue ends which join with the liner. The length of the openings may be considerably more than the width of the tongues, perhaps twice as much, so that when the tongues are interlocked with such openings the liner ends thus secured are still free to slide one upon the other in a longitudinal direction. The connection, thus made, is accomplished readily by bending and then straightening the tongues for interfitting within the openings. Once this is done, the tongues will tend to remain in their locked positions. To make such connection permanent, if desired, a small strip of tape or paper p may be adhered over the tongues t. This sticker or label which may carry printed matter, as desired, is applied in place through a window opening w between the slots o, and remains visible therethrough as indicated clearly in Figs. 1 and 5.

In the packing of a container, as, for example, a bushel basket, the liner may be called upon to contract or expand in longitudinal directions, according to the manner in which the pack is made. Provision for all such movements is made by the slip connection described. This connection which is of exceeding simplicity may be made quickly at the time the liner is used, or, if desired, at the factory before the liner is shipped. When the liner ends are connected, prior to packing and shipping, the thickness at the joined ends will about balance the thickness at the creased ends, so that a pile of such liners tied together or packed for shipment will make for greater economy in space.

I claim:

1. A package liner of elongated form having at one end slits which define tongues extended transversely toward each other and at its other end closed slots extended longitudinally with which the tongues are adapted to interfit to connect the liner ends together, and means joining the adjacent ends of the tongues whereby to inseparably the connection between the liner ends.

2. A package liner of elongated form having

at one end slits which define tongues extended transversely toward each other and at its other end closed slots extended longitudinally with which the tongues are adapted to interfit to 5 connect the liner ends together, there being also a window opening between the closed slots, and means applicable through the window opening remaining visible therethrough joining the adjacent ends of the tongues whereby to inseparabilize the connection between the liner ends. 10 3. A package liner of elongated form having opposite ends connected by transversely disposed tongues formed integral with the liner at one end interfitted with slots formed in the other 15 end of a length exceeding the width of the

tongues whereby to provide a slip joint, and separate means joining only the tongues together whereby to inseparabilize the connection between the liner ends without interfering with slip movement therebetween. 80

4. An elongated package liner having its opposite ends formed with integral cooperating locking means providing a connection therebetween, there being a window opening adjacent one liner end, and separate means insertable through the window opening and remaining visible therethrough joining together the locking means on the other liner end whereby to prevent disconnection of said cooperating locking means. 85
